UNITED STATES PATENT OFFICE.

ERNEST C. GEIER, OF NEW YORK, N. Y., ASSIGNOR TO DUPLAN SILK CORPORATION, OF NEW YORK, N. Y., A CORPORATION OF NEW YORK.

DESIGN FOR AN ARTIFICIAL SILK TEXTILE.

60,529.

Specification for Design.

Patented Mar. 7, 1922.

Application filed May 28, 1921. Serial No. 473,412. Term of patent 3½ years.

To all whom it may concern:

Be it known that I, ERNEST C. GEIER, a citizen of the Swiss Republic, residing at New York, in the county of New York and State of New York, have invented a new, original, and ornamental Design for an Artificial Silk Textile, of which the following is a specification, reference being had to the accompanying drawing, forming part thereof.

Figure 1 is a perspective view of a piece of artificial silk textile showing my design as seen from the back of the fabric.

Figure 2 is a front perspective view of the fabric shown in Figure 1.

Referring to the drawings, a piece of fabric is shown which forms a backing or body through which a series of closely placed strands of artificial silk are interwoven, the strands being woven through the fabric at longitudinally spaced points, thereby producing a series of transverse raised ridges presenting a substantially continuous undulating appearance, separated by transverse strips of the backing material.

I claim:

The ornamental design for an artificial silk textile, as shown.

ERNEST C. GEIER.
